Primary Examiner—Nanda Bondade*Assistant Examiner*—Shanda C. Hill(74) *Attorney, Agent, or Firm*—Fitch, Even, Tabin & Flannery(57) **CLAIM**

The ornamental design for a container with lid, as shown and described.

DESCRIPTION

FIG. 1 is a top perspective view of a container with lid showing our new design;

FIG. 2 is an exploded perspective view thereof;

FIG. 3 is a top perspective view thereof with the lid removed; shown separately for clarity of illustration

FIG. 4 is bottom perspective view thereof;

FIG. 5 is a front elevational view of FIG. 1, the rear, left and right views being identical thereto;

FIG. 6 is an exploded front elevational view thereof, the rear, left and right views being identical thereto; and,

FIG. 7 is a bottom plan view thereof.
